Assistant Examiner — Alexandria Dubus

(57) CLAIM

The ornamental design for a card box, as shown and described.

DESCRIPTION

FIG. 1 is a front, top perspective view of a card box, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the card box, shown in a position of use with exemplary cards.

The broken lines are shown for the purpose of illustrating environmental subject matter of the exemplary cards that do not form part of the claimed design.

1 Claim, 9 Drawing Sheets
